United States Patent Office

Des. 229,666
Patented Dec. 25, 1973

229,666

APPLIANCE HANDLE

Paul F. Frawley, Georgetown, Ontario, Canada, assignor to John Inglis Co. Limited, Toronto, Ontario, Canada

Filed July 21, 1972, Ser. No. 273,821

Term of patent 14 years

Int. Cl. D8—06

U.S. Cl. D8—169

FIG. 1 is a perspective view of the appliance handle.
FIG. 2 is a side view of the appliance handle.

FIG. 3 is a front view of the appliance handle shown foreshortened for convenience of illustration.

FIG. 4 is a top view of the appliance handle.

FIG. 5 is a view of the bottom end of the appliance handle.

I claim:

The ornamental design for an appliance handle, as shown and described.
